UNITED STATES PATENT OFFICE.

HARRY S. HANSTINE, OF PITTSBURG, PENNSYLVANIA, ASSIGNOR OF TWO-THIRDS TO JAMES D. CRAFFT AND LEWIS E. MONTGOMERY, OF OAK-MONT, PENNSYLVANIA.

VISE.

SPECIFICATION forming part of Letters Patent No. 757,918, dated April 19, 1904.

Application filed August 18, 1903. Serial No. 169,932. (No model.)

To all whom it may concern:

Be it known that I, HARRY S. HANSTINE, a citizen of the United States of America, residing at Pittsburgh, in the county of Allegheny and State of Pennsylvania, have invented certain new and useful Improvements in Vises, of which the following is a specification, reference being had therein to the accompanying drawings.

10 This invention relates to certain new and useful improvements in vises, the primary object of the invention being to construct a vise in which the jaws are capable of being inclined to different positions or angles, whereby to bring said jaws to any desired position, and, furthermore, to provide a vise in which one of the jaws is adjustable independently of the other jaw, whereby to position the jaws to conform to the particular shape of piece being held.

15 A further object of the invention is to provide a vise of a simple and effective nature comparatively inexpensive to manufacture; and the invention resides in the novel construction, combination, and arrangement of parts to be hereinafter more fully described, and specifically pointed out in the claims.

20 In describing the invention in detail reference is had to the accompanying drawings, forming a part of this application, and wherein like numerals of reference indicate like parts throughout the several views, in which—

25 Figure 1 is a central vertically-longitudinal sectional view of my improved vise. Fig. 2 is a horizontal sectional view of the same. Fig. 3 is a top plan view, the jaws being partly broken away. Fig. 4 is a cross-sectional view taken on line 4 4 of Fig. 1. Fig. 5 is a plan view of the bearing-nut for the outer jaw. Fig. 6 is a detached detail perspective view of the adjusting-ring. Fig. 7 is a detached detail plan view of the convexo bearing-nut. Fig. 8 is a front view of the socket member or shell of the vise. Fig. 9 is a longitudinal 30 sectional view of the same. Fig. 10 is a detached side elevation of the lock-arm for holding the jaws in the adjusted position. Fig. 11 is a plan view of the same. Fig. 12 is an un-

derneath plan view of the bed-plate of the vise. Fig. 13 is a horizontal sectional view 50 of the same. Fig. 14 is a detached detail perspective view of the inner jaw. Fig. 15 is a like view of the barrel on which the jaws are mounted. Fig. 16 is a similar view of the outer jaw.

55 To put my invention into practice, I provide a barrel 1, which receives the operating-screw 2 therethrough and is slotted, as at 3, from its inner end to a point near its outer end in order to permit its passage through 60 the segmental openings 3', provided therefor in the convexo lock-nut 4. The providing of the lock-nut 4 with the segmental openings 3' forms a spider 4', having the threaded opening 5' to receive the operating-screw 2. This 65 screw has a stem 5 extending through the shank 6 of the barrel and having connected to its outer end, as by a pin 7 or other approved means of connection, a T 8, which receives the operating lever or handle 9 of the usual 70 form of construction. The segmental cut-away portions 3' besides receiving the barrel 1 also receive the sleeve 11, which carries the inner jaw 12, this sleeve surrounding the barrel 1 and being held by means of a jam-nut 14, threaded onto its inner end. In order 75 to pass the sleeve through the nut 4, it will of course be evident that the sleeve must be provided with a slot 11', and in casting the parts it is the practice to cast the jaw 12 and 80 the sleeve integral, providing the core, which leaves a portion of the sleeve unslotted at its inner end in order that the thread may be readily cut on said nut, and after this thread is cut the portions are chiseled out to extend 85 the slot through to the inner end of the sleeve. The jaw 12 is provided on its rear face with an annular flange 15, which engages the concave lip or extension 16, carried by the body or bed plate 17, and also engages the convexo 90 faces 20, carried by the socket member or shell 21, the substantially elliptical-shaped opening 22 of which receives the sleeve 11 and barrel 1. The shell or socket member is made integral with the bench-plate 19, which 95 is suitably bolted or otherwise secured to the

bench or other support. (Not shown.) This bench-plate is provided in its forward edge with a cut-away portion to receive the plate 17 and is provided on its underneath face 5 with a rib 18, having a beveled forward face 18' to receive the beveled edge 16' of the plate 17. The plate 17 and its curved extension 16 is merely a filling-in piece and is only intended to be used in connection with the vise when 10 the latter is in its lowermost position—that is, the position shown in Fig. 1. The purpose of plate 17 is to prevent filings, shavings, or small tools from falling through the cavity which it fills, and it is removed when 15 the vise is to be raised above the position shown in Fig. 1. The socket member 21, as stated, is integral with the bench-plate 19 and at its lower end is provided with a curved slot 23, through which is passed the curved 20 guide-arm 24, which also acts as one of the instrumentalities for holding the vise in the adjusted position. This curved guide-arm is adapted to be moved within the curved slot and is securely held in any desired position 25 by means of a set-screw 26 or other desirable securing means, the arm having a head 25, which acts as a stop to limit the movement of the arm in one direction. This stop is adapted to engage in the opening 28 provided 30 therefor in the socket or shell 21 and shaped correspondingly to the shape of the head or stop 25.

The purpose of curved arm 24 is to assist in holding the vise when it is adjusted at 35 an angle to the top of the bench, the arm being held at its upper end by the flange 15 of the inner jaw 12 and the curved arm being held when the vise is raised by the set-screw 26.

On the shank 6 of the barrel is an annular 40 beveled shoulder 29, and surrounding this shoulder is an independently-adjustable outer jaw 30, provided on its outer face with a concave seat 31, its inner face being provided with a seat 31', surrounding the opening and 45 through which the shank 6 extends and conforming to the seat or shoulder 29 of said shank. A nut 32 is loosely mounted on the shank 6, the said nut having an elliptical-shaped opening 32' to receive the shank and 50 having a convexo face 33 to engage with the concave seat 31 of the jaw 20, this nut being held on shank 6 by means of the jam-nut 34, threaded onto the outer end of the shank 6 of the barrel. The nut 32 is recessed in its 55 outer face, as at 34', and the walls of this recess have two oppositely-disposed straight-line faces 35, that are engaged by the two oppositely-disposed straight-line faces 36, provided on the adjusting-ring 37, which is 60 seated in the recess 34' in the outer face of nut 32. This adjusting-ring has a substantially oblong opening 38, on opposite walls of which are inclined faces 38', which engage with opposite faces of the shank 6 and lie at 65 an acute angle to the faces 35. Connected

to the ring is an adjusting-screw 39, the neck 40 of which operates in the wall of nut 32. It will be observed that when this screw 39 is turned the adjusting-ring 37 will be moved within the recess 34', moving the adjusting-ring laterally within the recess and adjusting the position of nut 32, according to the direction in which the screw 39 is turned. After the jaw 30 has been adjusted to the desired angle it is held by means of a set-screw 41, which impinges against seat 29 of the shank 6, or other approved locking means may be employed. The nut 32, it is to be noted, is loosely mounted, thereby permitting sufficient clearance between this nut 80 and the shank of the barrel to permit of the rocking movement of the nut on the shank, and it is to be noted that when the adjusting-ring is actuated so as to incline the nut to the vertical—that is, for instance, force the upper half of the nut toward the jaw 30 and lower half of the nut away from the jaw 30, or vice versa—that the jaw can then be inclined accordingly with respect to the jaw 12, and after adjusted to the desired position the 90 jaw 30 is securely held by tightening set-screw 41.

The loosening of set-screw 26 enables both of the jaws to swing, the vise swinging in its bearings, so as to bring parts to the desired 95 position, either at an incline to the vertical or at an incline to the horizontal line, or both, as may be desired. The provision of means which permits the independent adjustment of the outer jaw enables me to adjust this jaw 100 whereby to accommodate tapered or other special shapes which it may be desired to hold.

It will be obvious that various slight changes may be made in the details of construction without departing from the general 105 spirit of my invention.

Having fully described my invention, what I claim as new, and desire to secure by Letters Patent, is—

1. In a vise, the combination of a socket member having a substantially elliptical-shaped opening and provided with a curved slot, a sleeve extending through the elliptical-shaped opening, a barrel telescoping said sleeve and having a stem, an outer jaw adjustably mounted on said stem, means for locking said outer jaw in the adjusted position, a nut receiving the said sleeve and barrel, an operating-screw engaging said nut, a guide-arm 115 engaging in the curved slot of the socket member, an inner jaw carried by the sleeve and means for engagement with the guide-arm to secure the inner jaw in an adjusted position.

2. In a vise, the combination of a socket member, a sleeve telescoping therein, a barrel telescoping the sleeve and provided with a stem, a nut receiving the barrel and sleeve, an operating-screw engaging the nut, an inner 125 jaw mounted on the sleeve and adjustable to 130

inclines at an angle to the vertical, means for securing said inner jaw in the adjusted position, an outer jaw adjustably mounted on the stem of the barrel, and means for securing the outer barrel in its adjusted position.

5. In a vise, the combination of a socket member, a sleeve telescoping therein, a barrel telescoping said sleeve a nut receiving the barrel and sleeve, an operating-screw engaging said nut, a jaw carried by said sleeve, and a coacting jaw adjustably mounted on the stem of the barrel, substantially as described.

6. In a vise, the combination of a socket member, a sleeve engaging in said socket member, a barrel telescoping said sleeve, a jaw carried by the sleeve and provided with an annular flange engaging a convex face of the socket member, a coacting jaw mounted on the barrel, means whereby said jaws are adjusted in unison, and means for adjusting the coacting jaw independently of the first-named jaw.

7. In a vise, a socket member, a sleeve telescoping the socket member, and a barrel telescoping the sleeve and provided with a stem, an inner jaw mounted on the barrel and adjustable to inclines at an angle to the vertical, means for securing said jaw in the adjusted position, an outer jaw mounted on the stem

of the barrel and adjustable to inclines at an 30° angle to the vertical independently of the inner jaw, and means for securing the outer jaw in the adjusted position.

8. In a vise, a pair of coacting jaws mounted for adjustment independently and in unison to inclines at an angle to the vertical, and also for adjustment independently and in unison at an angle to the horizontal, means for securing one of the jaws in the adjusted position, and separate means for securing the other of said jaws in the adjusted position.

9. In a vise, a socket member, a sleeve telescoping the socket member, an inner jaw carried by the sleeve and adjustable to inclines at an angle to the vertical, means for securing said jaw in the adjusted position, a barrel telescoping the sleeve, an outer jaw mounted on the barrel and adjustable to inclines at an angle to the vertical independent of the inner jaw, and means for securing said outer jaw in 50° the adjusted position.

In testimony whereof I affix my signature in the presence of two witnesses.

HARRY S. HANSTINE.
